United States Patent Office.

WILLIAM STOKES, OF NEW YORK, N. Y.

Letters Patent No. 105,274, dated July 12, 1870.

IMPROVEMENT IN SUSPENSION PAPER-CLIPS.

The Schedule referred to in these Letters Patent and making part of the same.

To all whom it may concern:

Be it known that I, WILLIAM STOKES, of the city, county, and State of New York, have invented a new and improved Card-Suspender and Clasp; and I do hereby declare that the following is a full, clear, and exact description thereof, which will enable others skilled in the art to make and use the same, reference being had to the accompanying drawing forming part of this specification.

The present invention relates to a new and useful device for suspending and holding cards, &c., the construction and operation of which will be fully understood from the following description.

Figure 1 represents a front view of my device, showing the same clasped to a card, and suspended from a cord.

Figure 2 is a side view of the same.

Similar letters of reference indicate corresponding parts.

This suspender and clasp is constructed of sheet metal, suitably tempered, to give the amount of spring necessary for its specific purpose.

In this case the letters A A represent two slots, stamped or cut through the back portion of the clasp-plate, and B B represent two lips, likewise cut and bent inward at right angles to the upper portion of the clasp-plate, so that the points of the said lips may just enter the lower part of the aforesaid slots.

The clasp-plate is bent over, so as to form a spring loop, C, at its top, which will serve to keep the shoulder of the catch, which is on the lips B B, forced downward, and locking over the lower edge of the slots on the clasp-plate, thus holding itself secure, without bending over the points B, when set on a card, as is now commonly done.

The suspending device consists of a circular piece of sheet metal, D, whose inner portion E is partially stamped or cut through, leaving a neck, F, which is bent outward sufficiently to allow it to slide freely on a cord, from which it cannot be detached without first forcing out the inner portion E, which forms a spring to hold it in its place.

Having thus described my invention,

What I claim as new, and desire to secure by Letters Patent, is—

An improved self-perforating show-card fastener and suspender-lock, consisting of the circular piece of sheet metal D, having inner part E, the slotted spring loop C, and lips B B, all constructed and adjusted together as and for the purpose specified.

The above specification of my invention signed by me this 22d day of October, 1869.

WILLIAM STOKES.
